J. J. KEGLER

BROMO SELTZER DISPENSER

Filed Jan. 29, 1921

Inventor
John J. Kegler
By J. M. St. John
Atty.

UNITED STATES PATENT OFFICE.

JOHN J. KEGLER, OF CEDAR RAPIDS, IOWA.

BROMO-SELTZER DISPENSER.

Application filed January 29, 1921. Serial No. 441,069.

To all whom it may concern:

Be it known that I, JOHN J. KEGLER, a citizen of the United States, residing at Cedar Rapids, in the county of Linn and 5 State of Iowa, have invented certain new and useful Improvements in Bromo-Seltzer Dispensers; and I do hereby declare the following to be a full, clear, and exact description of the invention, such as will enable 10 others skilled in the art to which it appertains to make and use the same.

This invention relates to the dispensing of measured quantities of substances in granular or powdered form, and more particularly 15 such substances as bromo-seltzer, and the like, as dispensed in drug-stores.

The object of the invention is to provide such stores with a simple, automatic measuring device adapted to deposit in a glass a 20 normal dose of bromo-seltzer, or other powdery substance usually sold in regular, predetermined quantities.

The invention is fully described and claimed in the specification following, reference being had to the accompanying drawing, in which:—

Fig. 1 is a side elevation of a dispensing device embodying my invention. Fig. 2 is a central, vertical section, showing the working parts of the same. Fig. 3 is a plan view of the powder chamber.

In the drawing, the numeral 1 denotes a base, to which is secured a vertical, tubular standard 2. Connected with the standard 35 near its upper end is a horizontal arm 3, to the outer end of which connects a vertical, tubular receiver 4, open at both ends, the lower end being somewhat constricted. The neck, as the horizontal arm may be 40 briefly designated, carries a bushing 5, which serves as a bearing for a spindle 6. To the end of the spindle projecting into the standard is secured a spiral cam 7 by which a partial rotation is imparted to the spindle by the 45 movement of a fork 8, having pins 9 in register with the grooves in the cam. The fork forms part of a lever 10 pivoted at 11 in a slotted bearing-block 12. The offset lower end of the lever projects outwardly through 50 a slot 13 in the standard, and is provided

with a foot-plate 14 having an upstanding shoulder 15. The foot serves as a rest for a glass 16, by means of which the operator pushes the foot of the lever backwardly, and so rotates the spindle. A suitable spring 55 10^a serves to restore the lever to normal. To the outer end of the spindle is attached a measuring receptacle 17. This is shown provided with a square socket 18, which registers with a similar throat 19 in a diaphragm 20 mounted above it. The outside 60 of the measuring cup, here shown as spherical, fits neatly in a corresponding seat under the diaphragm, to prevent leakage. A complete movement of the lever imparts a half 65 revolution to the cup, and the contents drop through the outlet 21.

The chamber 4 is of the right diameter to receive the mouth of a bromo-seltzer bottle 22, which is inverted over it, and is held 70 steadily in position by a rubber band 23 around its neck.

It is evident that so long as a supply of the powder is provided the instrument is always 75 ready for use. The glass being placed in position on the lever foot, is pushed back, and catches the dose of powder as it falls.

As ordinarily dispensed there is apt to be uncertainty in the size of the dose, with incident waste of material, and an unsanitary 80 scattering of powder, which must be repeatedly wiped up. There is also the loss of time in getting down the bottle, removing the cork, and measuring, or guessing at the dose. The device as described is designed to 85 provide better means for dispensing such drugs as have been indicated, and which are in constant and universal demand.

Having thus described my invention, I claim:—

1. In a dispensing device, a receiving chamber, a rotative cup mounted therein, a spiral cam connecting with the cup, and a lever co-operating with said cam to reverse the position of the cup.
2. In a dispensing device, a bottle-holding receiving chamber, a rotative cup mounted in said chamber, a spindle therefor a spiral cam on said spindle, a forked lever engaging said cam, and an outstanding foot on the 100

lever, below the cup, whereby the lever may be pushed by a glass receiving the discharge from the cup.

3. In a dispensing device, a receiver adapted to hold the mouth of an inverted bottle, a rotative cup mounted therein, a spindle therefor, a spiral cam on the spindle, a supporting standard, a forked lever engaging the cam, and pivoted to the standard, and

having a projecting foot whereby it is actuated to oscillate the cup.

In testimony whereof I affix my signature in presence of two witnesses.

JOHN J. KEGLER.

Witnesses:

C. E. LEIGH,
AUGUSTO NAILEN.
